Primary Examiner — W. A. Teddy Falloway*Assistant Examiner* — Melissa A Santos(74) Attorney, Agent, or Firm — Hawaii Patent Services; Nathaniel K. Fedde; Kenton N. Fedde(57) CLAIM

The ornamental design for a wall lamp as shown and described.

DESCRIPTION

FIG. 1 is a front perspective view of a wall lamp showing my new design;

FIG. 2 is a rear perspective view thereof;

FIG. 3 is a front elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear elevation view thereof.

The broken lines in the figures are for the purposes of illustrating portions of the wall lamp, which form no part of the claimed design.

1 Claim, 6 Drawing Sheets(56)
